DESIGN FOR A MOTOR GENERATOR SET CABINET

Edwin C. Worthley, Minneapolis, Minn.

Application March 24, 1943, Serial No. 109,814

Term of patent 14 years

To all whom it may concern:

Be it known that I, Edwin C. Worthley, a citizen of the United States, residing at Minneapolis, in the county of Hennepin and State of Minnesota, have invented a new, original, and ornamental Design for Motor Generator Set Cabinets, of which the following is a specification, reference being had to the accompanying drawing, forming part thereof.

Referring to the drawing, the single figure of the drawing is a perspective view of a motor generator set cabinet, showing my new design, the far side of the cabinet being the same as the side illustrated, and the back thereof being plain.

I claim:

The ornamental design for a motor generator set cabinet, as shown and described.

EDWIN C. WORTHLEY.
